Inventor

William H. Bradt

United States Patent Office.

WILLIAM H. BRADT, OF NEW SCOTLAND, NEW YORK.

Letters Patent No. 97,867, dated December 14, 1869.

IMPROVEMENT IN WAGON-BRAKES.

The Schedule referred to in these Letters Patent and making part of the same

To all whom it may concern:

Be it known that I, WILLIAM H. BRADT, of the town of New Scotland, county of Albany, State of New York, have invented certain Improvements in Wagon-Brakes; and I do hereby declare that the following is a full, clear, and exact description thereof, reference being had to the accompanying drawings, forming a part of this specification, in which—

Figure 1 is a perspective view of the forward part of a wagon, viewed from beneath, illustrating my invention.

Figure 2 is a side elevation of the same, embodying the invention.

The first part of my invention relates to a combination, with a backing-rod furnished with a tooth on its front end, and working in a slotted plate, secured to the end of the wagon-pole, of a T-head and slot on the rear end of the said backing-rod, in such a manner that the said backing-rod will be held up in its place on the under side of the pole, and at the same time be capable of being moved longitudinally to operate the other parts of this invention, when the wagon is descending an incline.

The second part of my invention relates to an operation of the rear end of the backing-rod, with a sliding bar, attached to the lower side of the hounds, which will be capable of affecting the several levers and rods which operate the brake-bar when the backing-rod shall be pushed back; the object of this part of my invention being to secure an operation of the brake through the medium of the backing-rod, and at the same time to allow the pole to be freely vibrated vertically in either direction, without straining any part of the wagon or its adjuncts.

The third part of my invention relates to the combination of brake-levers with pushing and drawing-rods in such a manner that the said levers shall be capable of being set, so that their long ends, to which the pushing-rods are attached, may have their distance from their fulcrums lengthened, or shortened, as circumstances might require; the object of this part of the invention being to make the same brake perfectly adapted to all localities with their varied grade of hills or descents, and so afford no excessive action of the brake by the average grade of such descents in the localities the brake may be used.

To enable others skilled in the art to make and use my invention, I will proceed to describe, in reference to the drawings, and the letters of reference marked thereon, the same letters indicating like parts.

In the drawings—

A represents the forward axle of a wagon.

B are the wheels.

C are the hounds.

D is the pole.

E is the sand-bar.

Attached to the end of the pole D, on its under side, is a slotted guide-plate, a, figs. 1 and 2, which plate a is properly secured either by bolts or screws b, and is capable of being shifted either back or forward, for the purpose hereafter described.

The said plate is provided with a slot, c, about three or four inches long.

Placed below the pole is a rod, d, which I denominate the backing-rod, which backing-rod has formed on its forward end a holdback-piece, e, which I term the tooth.

The said tooth e projects down from the under side of the pole, through the slot c in the plate a, and can be worked forward or backward in the said slot c, moving the rod d.

The rear end of the backing-rod d is provided with a T-head, f, formed vertically back of the rear end of the pole.

Just forward of the said T-head, and in the said rod d, is a slot, which slot works outside the bolt g, which passes through the pole D vertically, and holds up the said rod d, and permits a longitudinal movement of the said rod.

Placed across the hounds C, on their lower back of the pole, and in conjunction with the rod d, is a bar, h, which I denominate the snuing bar.

The said sliding bar is held in place up to the said hounds by the staples i, which staples are secured to the hounds C.

The said sliding-bar is also provided with holes, each at a little distance from its centre, to receive the pivot-ends of its connecting-rods, which it is to operate, and the said bar h is itself affected and operated by the T-headed end of the rod d, when the said rod d is crowded back.

Pivoted to the hounds C, back of the axle, are the levers k, which levers are provided with several holes l, in their longest ends, any of which holes l may receive the rear pivot-ends of the pushing-rod m, to effect the desired movement of the said levers, as may be communicated by the said rods m from the sliding bar h, with which the rods m connect.

The rods m pass back from the bar h to the said levers k, through the space between the axle-bed A and the sand-bar E, as shown in fig. 2, and are steadied laterally by means of eyes n, secured to either the said axle-bed or the sand-bar.

Connecting with the short end of the levers k, are the drawing-rods o, which connect with the usual brake-bar P, in any suitable manner, and operate it.

Placed forward of the brake-bar P, and attached thereto, and back of the sway-bar q, is the spring r. The ends of the said spring may be made to bear either against the back of the said sway-bar, or against

any suitable support attached to the hounds, so that a backward pressure is furnished to the brake-bar P.

The manner in which this brake operates, is as follows:

In the descent of any grade, the ring of the neck-yoke, drawing back on the tooth c, causes the rod d to move back, so that its T-headed end f will press against the sliding bar h, and crowd it back to a distance limited by the staples i, which crowding back will effect a backward pushing to the rods m, which, in their turn, will affect the levers k more or less, according to the distance the rear pivot-ends of the rods m may be set from the fulcrum of the said levers. When thus affected, the said levers will pull on the rods o, and draw the brake-bar P forward, and force the brake-blocks s in contact with the wheels B.

When the descent has been passed, and the ring of the neck-yoke has released its pressure on the tooth c, the spring r will throw the brake-bar P back, and effect a reverse movement of all parts of the brake, preparatory to some subsequent action.

Should the general grades of hills or descents in a locality be but slight, I would pivot the pushing-rods m to the levers k near to their fulcrum, and also secure the plate a at the end of the pole forward. If such descent were great, I would pivot the said rods m at the ends of the levers k, and shift the plate a to back, as shown by dotted lines in fig. 2, but if a medium grade,

I would pivot them between the nigh and further poles l in the said levers, and place the plate a as to correspond; and by so doing in either case, I can adapt, and make the brake suitably efficient for the general grade of descents over which the wagon is to usually travel.

By reason of the non-attachment of the pushing-rod d with the bar h, and the action of the said rod d on the said bar h by conjoining contact, only the end of the pole of the wagon can be raised up or thrown down without endangering, straining, or otherwise affecting any part of the wagon or its appurtenances.

Having described my invention,

What I claim, and desire to secure by Letters Patent, is—

1. The combination and arrangement of the T-head, pushing-bar d, sliding cross-bar h, pushing-rods m m, levers k k, draw-rods o o, and shoe-bar P, for the purpose set forth.

2. The combination and arrangement of the levers k k, provided with graduating-holes l l, or their equivalents, the drawing-rods o o, and shoe-bar P, when motion is communicated to said levers by the pushing-rods d m m, or the equivalents of these parts.

WILLIAM H. BRADT.
